UNITED STATES PATENT OFFICE.

ISAAC HOLDEN, OF BRIDGEPORT, CONNECTICUT, ASSIGNOR TO THE WHEELER
& WILSON MANUFACTURING COMPANY, OF SAME PLACE.

INDICATOR.

SPECIFICATION forming part of Letters Patent No. 355,531, dated January 4, 1887.

Application filed September 24, 1886. Serial No. 214,428. (No model.)

To all whom it may concern:

Be it known that I, ISAAC HOLDEN, a citizen of the United States, residing at Bridgeport, in the county of Fairfield and State of Connecticut, have invented certain new and useful Improvements in Indicators; and I do hereby declare the following to be a full, clear, and exact description of the invention, such as will enable others skilled in the art to which it applies to make and use the same.

My invention relates more especially to the class of "indicators" or "information tablets" of which the devices illustrated in Patents No. 258,529, dated May 23, 1882, and No. 15 307,705, dated November 4, 1884, are examples, it being of course understood that the principle herein described and claimed is equally applicable to counting and calculating machines, to bills of fare, and in fact to all machines of this general class.

My invention has for its object to simplify and cheapen the construction, and at the same time to greatly improve the general operation of this class of machines. With these ends 25 in view I have devised the novel construction of which the following description, in connection with the accompanying drawings, is a specification, numbers being used to indicate the several parts of the device.

30 In the drawings, Figure 1 is a front elevation of the indicator in its open position, ready for use; Fig. 2, a similar view, showing it in operation; Fig. 3, a rear elevation, the cover and equalizer being removed, showing the internal mechanism; Fig. 4, a vertical section on the line *xx* in Fig. 3; Fig. 5, an end elevation illustrating the mechanism for operating one of the drums detached; Fig. 6, an enlarged cross-section illustrating the mechanism for adjusting the key-board. Figs. 7 and 8 are enlarged 35 detail perspectives illustrating different forms of fingers; Fig. 9, a plan view of one of the Jacquard keys; and Figs. 10 and 11 are detail views, showing the surfaces of the drums as laid out on a plane.

45 Similar numbers denote the same parts in all the figures.

1 denotes the casing, which may be of any desired shape or construction, and 2 station-signs pivoted in the central portion of the casing. These station-signs may be of any

preferred style, and, as shown in the drawings, are operated in the same manner as in Patent No. 307,705, referred to above.

3 denotes the Jacquard key, which in use is 55 held in operative position on key-board 4 by pins 4^a, engaging holes 5, or in any suitable manner.

6 denotes a series of drums journaled on a fixed shaft, 7, which are adapted to bear upon 60 their peripheries signs or distinguishing marks—for example, letters or numerals to indicate the time of departure of trains. These drums may of course be cylindrical or polygonal; or, if preferred, disks may be used 65 with numerals or other characters upon the sides thereof.

8 is a drum, preferably polygonal in form, upon which I place signs descriptive of the different classes of trains. This drum is preferably 70 fixed to its shaft 9, both shafts being supported by suitable frame-work, 10, within the casing.

10^a denotes openings in the front of the casing, through which the signs or marks upon 75 the drums may be seen.

11 denotes the rods by which the station-signs are operated, there being an independent rod for each sign, and 12 the rods through which the drums are operated, there being only 80 one rod for each drum, no matter how many independent numerals or other signs may be upon the drum, as will presently be more fully explained.

13 denotes a cross-piece secured in the casing, through which the rods pass freely, the cross-piece serving as a guide therefor.

14 denotes a pair of sliding cross-pieces rigidly connected by rods 15, through which rods 11 and 12 pass, the same as through cross-piece 90.

13. The sliding cross-pieces move up and down in the casing, being operated by a crank-shaft, 16, which is engaged by a detachable handle, 17, at the front. (See Figs. 1 and 2.) A link, 18, connects the crank with a sleeve, 19, swiv-

eled in block 20, said block being firmly secured to the lower sliding cross-piece, as clearly shown in Fig. 6. I have provided the lower end of the link with a screw-thread, 21, which passes loosely through the sleeve, a perfect adjustment of said link being secured by nuts 22

above and below the sleeve. In order to se-

cure the greatest possible durability I secure a metal casing, 23, in a recess in block 20, and secure the shank of the sleeve in said casing by a plate, 24, screwed to the shank and engage the inner end of the casing.

Turning now to Figs. 4 and 5, I will explain the mechanism whereby the drums are rotated.

As stated above, an independent rod is provided for each drum. A rack, 25, at the upper end of each rod engages a pinion, 26, secured to one of the drums or its shaft; or, if the construction should require, an intermediate gear, 27, may be used between the rack and pinion, as shown in connection with the lower drum in Fig. 5. The racks pass freely through and are guided by frame-work 10, as shown in Figs. 3 and 4. The most important feature of my invention, however, is the means by which I secure perfectly accurate automatic operation of the drums, no matter how many numerals or other signs may be upon them, but one rod being used for each drum.

28 denotes fingers or tumblers arranged in series or groups, these groups of fingers being rigidly secured at the lower ends of the rods 12, which connect with the drums through racks and pinions, as already described. The number of fingers or tumblers in each group is ordinarily one less than the number of signs which it is desired to display upon the drum with which the group is connected, as will presently be more fully explained.

The shape, arrangement, and construction of the fingers or tumblers are matters that may be varied to an almost unlimited extent without affecting the principle of my invention. In Fig. 7 I have shown them made separately and secured to a block, and in Fig. 8 I have shown a group of them formed from a single piece of metal. I preferably make each group of fingers or tumblers adjustable upon the rod by means of a set-screw, 29, or in any suitable manner. The fingers or tumblers in each group are graduated in length—for example, as shown in Figs. 7 and 8, *a* indicating the shortest finger in the group and *b* the longest, each finger in the series being slightly longer than its predecessor.

30 30 is a cross-piece firmly secured in the casing and provided with openings through which the fingers pass, the openings serving as guides. In order to prevent wear, and to provide firm lateral support for the fingers, I secure a 35 guard-plate, 31, upon the cross-piece, said guard-plate being provided with openings in which the fingers fit snugly, but are free to move.

In order to insure that all of the drums shall 60 be brought to any certain position, which I term their "normal" position—for example, the position in which they are shown in Fig. 1—every time the sliding cross-pieces are brought down by the crank, shaft, and link, 65 I provide collars 32, held in position on the rods by set-screws or in any suitable manner, which are engaged by the upper sliding cross-

piece each time it is brought down. This overcomes any friction of the rods or fingers in the guides, and thus insures absolute accuracy in 70 making the changes, as each finger is brought down before the cards are changed, as will be more fully explained. As I have found in practice that it is best to limit the downward movement of the groups of fingers or tumblers, 75 so that the ends will not strike or the bases come in contact with plate 31, I have provided other collars, 33, on the rods, which engage one of the fixed cross-pieces when the sliding cross-pieces are thrown down, whereby the 80 movement is checked at any desired position.

34 denotes a key-box, connected in any suitable manner to the lower sliding cross-piece, in which all the Jacquard keys, except 85 the special one in use, are kept.

The key-board is provided with openings (not shown) which register with the fingers. The Jacquard key used is the same as that described in Patent No. 258,529, referred to. In order to insure that the key-board shall 90 move upward and downward evenly and smoothly—that is, that there shall be no friction or binding in connection with either frame-work or fingers—I use an equalizer, 37, which operates in precisely the same manner 95 as that shown and claimed in Patent No. 307,705, referred to.

Turning now to Figs. 1, 2, and 9, I will explain in detail the operation of the drum-actuating mechanism.

As in the constructions shown in the patents referred to, a special key is prepared for each train in the daily series. In Fig. 1 the parts are at the opened position, the fingers or tumblers, rods, key-board, and key-box all being lowered. When the parts are in this position the Jacquard key corresponding with the train which it is desired to advertise is placed upon the key-board, holes 5 being engaged by holding-pins 4^a, as already described. Each key-board has holes punched through it corresponding in location with certain of the fingers. The key illustrated in Fig. 9 corresponds with the advertisement displayed in Fig. 2, the holes punched out being 115 indicated by circles in full lines, and the proper locations for holes to correspond with the remaining fingers being indicated by circles in dotted lines. The line of circles indicated by *c* belongs to the station-signs, which 120 form no part of my present invention. The single circle indicated by *d* corresponds with the finger or rod *D*, controlling the left drum in Fig. 2, which bears but one numeral. The group of circles indicated by *e* corresponds 125 with group *E* of fingers, which control the next drum toward the right, which bears nine numerals and zero. The group of circles indicated by *f* corresponds with group *F* of fingers, which control the third drum, bearing 130 five numerals and zero. The group of circles indicated by *g* corresponds with group *G* of fingers, which control the fourth drum, bearing nine numerals and zero. The group of

circles indicated by *h* corresponds with group H of fingers, which control the fifth or right drum, bearing the signs "Noon," "P. M.," "A. M.," and "Night." The group of circles indicated by *k* corresponds with group K of fingers, which control the lower drum, bearing signs denoting the different classes of trains, and also one blank space. A half-rotation of the crank-shaft from the position shown in Fig. 1 raises the key-box, closing it, as in Fig. 2, and at the same time throws the key-board to its operative position. A lug, 35, on the crank engages a pin, 36, just after it has passed the dead-center, and prevents the crank-shaft from completing the revolution, which would of course throw the key-board to the lowered position again. As it is, the key-board can only be lowered by a backward movement of the crank-shaft. Suppose, by way of illustration, that no key had been put in when the device was open, the half revolution of the crank-shaft to throw the parts from the position in Fig. 1 to that in Fig. 2 would have no effect upon the drums or signs, as all of the fingers and rods would pass through the openings in the key-board when the latter was raised. Likewise, if a key were used in which all the circles were punched out the result would be the same, as all the fingers and rods would pass through the holes in the key when the latter was raised, and would remain at their lowered position.

From the above it will be apparent that, in order to expose any particular signs or numerals upon the drums, it is necessary to turn them just sufficiently to bring the special numerals or signs desired into view at openings 10° and to stop the rotation at that point. This I accomplish by the engagement of the fingers with the key when the key-board is raised. In practice the circles in each group in the key are numbered or marked to correspond with the group of fingers which act in connection with them. (For fuller illustration see Patent No. 258,529, referred to.) To expose any numeral or sign, the circles in the corresponding group in the key are punched out from the end of the series back to but not including the circle corresponding with the numeral or sign which it is desired to expose. In the present instance the first finger in each group is shortest, and the last finger longest; but of course the series may be made to run the other way, if preferred—that is, the first finger may be longest and the last shortest. In other words, the holes corresponding with all fingers longer than the one to take effect are punched out, as the particular arrangement of the fingers is a matter of no consequence whatever. To illustrate, the key in Fig. 9 corresponds with the signs exposed in Fig. 2. As the numeral 1 upon the left drum is to be exposed, circle *d* is not punched out. As the numeral 2 is to be exposed on the second drum, 3, 4, 5, 6, 7, 8, and 9 are punched out from the group of circles in the key corresponding with the fingers for that drum. In the group of

circles belonging to the third drum 3, 4, and 5 are punched out to expose 2. In the group belonging to the fourth drum 9 is punched out to expose 8. There are no fingers corresponding with "Naught" on the second, third, and fourth drums, with "Night" on the fifth, or with the blank spaces on the first and lower drums. Consequently, to expose either "Naught," "Night," or a blank, all the circles must be punched out, so that the corresponding fingers will not be moved when the key-board is raised. In the group of circles corresponding with the fingers for the fifth drum "Noon" is punched out to expose "P. M." In the construction illustrated in the drawings an intermediate gear is used in connection with the lower drum. Consequently it rotates in the opposite direction. In the group of circles in the key belonging to this drum the first three are punched out to expose "Extra."

The specific operation of each drum—taking, for example, the second—is as follows: In the group of circles corresponding with the fingers for actuating this drum 9, 8, 7, 6, 5, 4, and 3 are punched out. Consequently the corresponding fingers pass through the holes when the key-board is raised, and no movement of the drum takes place up to this time; but as 2 is not punched out the corresponding finger is engaged by the key and carried upward by it, which movement, through the corresponding rod, rack, and pinion, imparts just sufficient rotation to the drum to leave the numeral 2 exposed at opening 10°.

I have used the term "circles" to define the marks upon the key corresponding with the fingers.

It will of course be understood that it is only necessary that the holes punched out should be of sufficient size to permit the corresponding fingers to pass through. The marks upon the key merely serve as guides to insure accuracy in punching the holes. Having once made a key to advertise a certain train, no change whatever is required until the train is changed.

I do not desire to limit myself to the exact details of construction shown and described, as it is obvious that the details may be widely varied without departing from the spirit of my invention.

I claim—

1. One or more drums having numerals or other distinguishing marks upon their peripheries, and means—for example, racks and pinions—for rotating said drums, in combination with a finger or group of fingers corresponding with each drum and a rod connecting each rack with its corresponding fingers.

2. A drum bearing signs or distinguishing marks and operating mechanism, substantially as described, in combination with a series of fingers corresponding with said signs and connected with the operating mechanism, a movable key-board and a Jacquard key having marks corresponding with the fingers, whereby

when said key is left imperforate at the mark corresponding with a certain finger and is perforated at the marks more advanced in the series said finger is raised and the corresponding sign upon the drum is exposed.

3. A series of drums bearing signs, mechanism for rotating said drums, and groups or series of fingers corresponding with said signs and connected with the rotating mechanism, 10 in combination with a key-board adapted to move upward independently of the fingers, as and for the purpose set forth.

4. The drums, the rods, racks and pinions by which they are operated, and frame-work 15 in which the drums are journaled and the racks guided, in combination with groups of fingers attached to the rods, a movable key-board, and a Jacquard key.

5. The casing having openings 10*, drums 20 having signs or marks adapted to be seen through said openings, and operating mechanism, substantially as described, in combination with groups of fingers or tumblers connected with said operating mechanism, and a 25 Jacquard key, whereby any desired signs or marks upon the drums may be exposed.

6. The drums, operating mechanism, as racks and pinions, and rods connected to said racks, in combination with collars 32, adjustably secured to said rods, and a sliding cross-piece 30 adapted to engage said collars in its downward movement, whereby all the drums are returned to their normal position.

7. The drums, operating mechanism, as 35 racks and pinions, and rods 12, connected to said operating mechanism and carrying fingers, as described, in combination with a fixed cross-piece which guides the rods, and collars 33 upon the rods, which engage the cross-piece 40 in the downward movement to prevent the fingers from striking.

8. The drums, operating mechanism, substantially as described, rods connected to the operating mechanism, and fingers 28, secured to said rods, in combination with cross-piece 45 13, which guides the rods, and cross-piece 30, having guard-plate 31, which guides the fingers.

9. In an indicator, rods 12, having collars 32, in combination with sliding cross-pieces 50 connected by rods, and operating mechanism--for example, a crank-shaft and link--whereby the cross-pieces are moved up and down, the collars being engaged by the upper cross-piece, as and for the purpose set forth.

10. In an indicator, the drums, operating mechanism, fingers, and sliding cross-pieces, substantially as described, and a crank-shaft and link whereby said cross-pieces are operated, in combination with swiveled sleeve 19, 60 to which the link is adjustably secured.

11. The drums, operating mechanism, sliding cross-pieces, block 20, secured to one of said cross-pieces, and swiveled sleeve 19, secured in said block, in combination with the 65 crank-shaft, link 18, pivoted thereto and threaded at its lower end, which passes through the sleeve, and nuts 22, whereby the link is adjustably secured in the sleeve.

12. The combination, with the drums, operating mechanism, substantially as described, rods 12, and fingers 28, of a key-board carried by sliding cross-pieces and a crank-shaft and link whereby said cross-pieces are operated.

In testimony whereof I affix my signature in 75 presence of two witnesses.

ISAAC HOLDEN.
